LAMP

Alexander E. Blumenthal, Pittsburgh, Pa.

Application March 27, 1950, Serial No. 8,801

Term of patent 3½ years

(Cl. D48—20)

To all whom it may concern:

Be it known that I, Alexander E. Blumenthal, a citizen of the United States, residing at Pittsburgh, in the county of Allegheny and State of Pennsylvania, have invented a new, original, and ornamental Design for Lamp, of which the following is a specification, reference being had to the accompanying drawing, constituting a part hereof.

Figure 1 is an elevational view, looking in any horizontal direction, of a lamp embodying my new design.

Fig. 2 is a fragmentary cross-sectional view thereof, taken on the line 2—2 of Fig. 1.

The dominant features of my design are shown in full lines in the drawing.

I claim:

The ornamental design for a lamp, substantially as shown and described.

ALEXANDER E. BLUMENTHAL
